PILL-COUNTING APPARATUS Anthony R. Miller, 2549 Blaisdell Ave., S.,
Minneapolis, Minn.

Filed Aug. 25, 1958, Ser. No. 756,798

6 Claims. (Cl. 198—30)

This invention relates to apparatus for handling pills for counting and the like and more specifically relates to apparatus for individually segregating pills from each other so as to facilitate ready and easy counting of the pills.

An object of my invention is to provide a new and improved apparatus of simple and inexpensive construction and operation for handling a volume of pills to facilitate counting thereof.

Another object of my invention is to provide a novel apparatus which will accept a large volume of small objects such as pills and the like and will string out the pills into a line to thereby facilitate counting of the pills as they pass a predetermined point.

These and other objects and advantages of my invention will more fully appear from the following description made in connection with the accompanying drawings wherein like reference characters refer to the same or similar parts throughout the several views and in which:

Fig. 1 is a top plan view of the invention;

Fig. 2 is a detail section view taken on a substantially vertical plane as indicated at 2—2 in Fig. 1.

One embodiment of the present invention is shown in the drawings and is described herein. The apparatus, which is indicated in general by numeral 10 includes a generally circular upright housing 11 having an open top 11b and having a supporting structure 11a in the bottom thereof to which is rigidly affixed a motor 12 having a drive shaft 12b to which is keyed a bevel gear 12c. The upper end of shaft 12b has a pill-carrying rotor 13 affixed thereon which is generally conically shaped and is convergent in an upward direction. The peripheral edge portion 13a of the rotor 13 is disposed in closely spaced relation with respect to the upright wall 11 but is movable with respect to the wall 11.

Means are provided for guiding and obstructing the rotary movement of the pills or other objects carried on the rotor 13, and in the form shown, such means include a quadrant-shaped rigid structure 14 affixed to the upright sidewall 11 of the housing and having a sloping bottom edge which is spaced from the conically shaped rotor 13 so as to allow the rotor to rotate thereunder and to prevent pills from moving beneath the structure 14.

A pill-guiding vane 15 is affixed to the structure 14 and extends generally outwardly from the central portion of the rotor 13 into proximity with the cylindrical sidewall 11 of the housing. It will be noted that the outer end portion 15a of the rigid and affixedly emplaced vane 15 is spaced from the sidewall 11. At the end of the rigid and stationary vane 15 is provided a flexible and thin membrane or filament 16 which is disposed immediately above the rotor 13 and extends outwardly into close proximity with the sidewall 11. The membrane 16 will be flexed under the influence of a pill being urged thereagainst by means of the rotor 13 so as to allow pills to pass by the vane 15 one at a time and along the peripheral wall 11 of the housing.

2

Means are provided for discharging the pills from the housing 11 as they pass by the membrane 16 one at a time. In the form shown, the housing sidewall 11 has an opening 17 therein at a position behind the vane 15 with respect to the direction of rotation of the rotor 13 as indicated by the letter A. One sidewall 14a of the structure 14 is disposed adjacent the side of the opening 17 so as cause the pills traveling on the rotor and past the membrane 16 to pass through the opening 17. A chute 18 is secured at the bottom edge of the opening 17 to direct the pills onto a conveyor belt 19 which is mounted on a rotary shaft 20 and a second idler roller 21 which are respectively mounted in bearings 22 mounted on an elongated frame structure 23 which is suitably affixed to the housing 11 and extending radially outwardly therefrom in alignment with the opening 17. The frame structure 23 defines upwardly extending walls 24 at the opposite sides of the conveyor 19 so as to maintain the pills on the conveyor. A plurality of deflector vanes 25 and 26 are affixed to the walls 24. It will be seen that the several vanes or panels 25 direct the pills toward one side of the conveyor and the vane 26 cooperates with the first vane 25 to assure that the pills will roll therealong and be carried on the conveyor in a single line. As the pills are guided by the vane 25 toward one side of the conveyor 19 they will be maintained in a single line and will be discharged off the end of the conveyor.

Means are provided for driving the conveyor in synchronism with the rotor 13 and in the form shown, a first shaft 27 is mounted in a suitable bearing 28 on the supporting structure 11a and has a pair of bevel gears 29 and 30 on the opposite ends thereof. The bevel gear 29 is in engaged and meshed relation with the bevel gear 12c and is driven thereby. The bevel gear 30 is engaged and meshed with another bevel gear 31 which is affixed to a drive shaft 32 which is mounted in suitable bearings 33. The other end of shaft 32 has another bevel gear 34 affixed thereon which is meshed with a bevel gear 35 on the conveyor driving shaft 20. The bevel gears 34 and 35 may be enclosed in a suitable protective housing 36 which is affixed as by screws 37 to the side wall 11 of the main housing.

Means are provided on the apparatus for counting the pills moved by the conveyor 19 and in the form shown, such means include a photoelectric cell 37 and a source of light 38 which are oriented in alignment with each other at the discharge end of the conveyor 19 and positioned so that the pills falling off the end of the conveyor 19 will break the beam of light entering the photocell 37 and will cause the counter 39 to be electrically operated so as to produce an accumulating total of the number of pills that are discharged from the conveyor. The counter 39 is of conventional construction, as are the photocell and light source 37 and 38 and the counter 39 has a suitable control means for operating the motor relay 40 when a predetermined number of pills have been counted so as to deenergize the motor relay and stop the motor.

In the operation of the present invention, the motor 12 will be operated at any one of three selectable speeds, either thirty-three r.p.m., forty-five r.p.m., or seventy-eight r.p.m. It has been found that to operate the motor at a rate of speed of thirty-three r.p.m. provides satisfactory results for handling pills up to five to six hundred pills per minute. After the motor 33 is started, the rotor 13 will revolve in the direction indicated by arrow A, and thereafter, a large quantity of pills may be poured indiscriminately upon the rotor 13. The pills will slide down the conically shaped rotor and will rest against the sidewall 11 of the housing. The rotating rotor will carry the pills around the housing and into engagement with the stationary vane 15 and into engagement with the flexible membranes 16 which will flex under the influence of the

force of the pills and will allow the pills to pass thereby one at a time. The pills will thereafter move toward the opening 17 and will roll off the edge of the rotor 13 and through the opening, down the chute 18 and onto the conveyor belt 19, whereupon the pills will strike either the vanes 26 or 25, but in any event will be guided to one side of the conveyor by means of the first vane 25 and the other second and third vanes 25 will maintain the pills in a single line as they pass along the belt conveyor and the pills will thereby pass through the light beam from the source 38 in a single line so as to cause operation of the counter 39 each time a pill breaks the light beam. It is contemplated that ordinarily pills will be supplied onto the rotor 13 in such numbers that the pills will not build up into a multiple layer accumulation adjacent the rotor periphery. However, even if the pills are slightly piled up adjacent the periphery of the rotor 13, the pills will still pass by the membrane 16, one at a time. It will be understood that most pills are smoothly rounded and it is quite unlikely that one pill will lie upon another pill in exact vertical alignment with the underlying pill. Because the underlying pill is being driven by the rotor 13, it will pass by the membrane 16, and if the second pill lying on the underlying pill is not exactly in vertical alignment in all respects with the underlying pill, the membrane 16 will engage the overlying pill and will flick it in a reverse direction as compared to the direction of travel of the rotor, or at least will restrain the overlying pill so that it does not pass by the membrane at the same instant as the underlying pill. It is conceivable that upon very infrequent occasions, two pills might pass the membrane 16 at one instant, but even if this occurs, the two pills will engage the surface 14a and be fed onto the conveyor belt 19 at different instances, so that the desired effect of stringing out the pills for counting purposes is accomplished.

It will be seen that I have provided a new and improved device for handling a large quantity of pills or other small objects for stringing out the pills into a single line to facilitate counting of the pills.

It will, of course, be understood that various changes may be made in the form, detail, arrangement and proportion of the parts without departing from the scope of my invention which consists of the matter described herein and set forth in the appended claims.

What I claim is:

1. Apparatus for segregating small objects such as pills and the like for counting the same one by one, comprising a substantially cylindrical retaining wall, an upwardly convergent tapered rotor inwardly of the wall and having a lower peripheral edge in closely spaced relation to the wall, means revolving the rotor on an upright axis substantially concentric of the wall, said wall having a pill-discharging opening at the edge of the rotor to allow pills to roll off the rotor and out the opening, a rigid, stationary vane above the rotor and extending from the central portion of the rotor into spaced relation with the wall at one side of the opening therein, an upright flexible membrane on the vane and extending therefrom to the wall and yielding under the influence of pills on the rotor to permit the pills to move one at a time between vane and wall and into the opening.

2. Apparatus for segregating small objects such as pills

and the like for counting the same one by one, comprising a substantially cylindrical retaining wall, an upwardly convergent tapered rotor inwardly of the wall and having a lower peripheral edge in closely spaced relation to the wall, means revolving the rotor on an upright axis substantially concentric of the wall, said wall having a pill-discharging opening at the edge of the rotor to allow pills to roll off the rotor and out of the opening, a rigid stationary vane above the rotor and extending from the central portion of the rotor into spaced relation with the wall at one side of the opening therein, an upright flexible membrane on the vane and extending therefrom to the wall and yielding under the influence of pills on the rotor to permit the pills to move one at a time between the vane and the wall and into the opening, an outwardly extending conveyor having a receiving end below the opening and in close proximity therewith, guide means at the opposite sides of the conveyor for retaining the pills on the conveyor, and an obliquely oriented stationary vane extending across the conveyor and directing the pills to one side thereof whereby to orient the pills in a single line as they move along the conveyor to facilitate counting of the pills one by one.

3. The invention set forth in claim 2 and including 25 a counter mechanism having a photoelectric cell at one side of the conveyor and a light source at the other side of the conveyor to sense the passing of pills one by one along the conveyor.

4. The invention set forth in claim 3 wherein said 30 photoelectric cell and light source are disposed at the discharge end of the conveyor to sense the discharging of pills from the conveyor.

5. The invention set forth in claim 2 and including a 35 pill-obstructing structure secured to the cylindrical wall and spaced above the rotor at the other side of the opening in the wall, whereby to prevent pills from passing by the opening as they move with the conveyor.

6. Apparatus for segregating small objects such as 40 pills and the like for counting the same one by one, comprising a substantially cylindrical retaining wall, an outwardly convergent tapered rotor inwardly of the wall and having a lower peripheral edge in closely spaced relation to the wall, means revolving the rotor on an upright axis substantially concentric of the wall, said wall having

45 a pill-discharging opening at the edge of the rotor to allow the pills to roll off the rotor and out the opening, means obstructing movement of the pills on the rotor and extending from the central portion of the rotor into proximity with the wall, said obstructing means and wall defining a space therebetween adjacent the edge of the rotor of such width as to accommodate the passage of pills therethrough one at a time, and an upright flexible membrane fixed in said space and yielding under the influence of pills on the rotor to permit the pills to move 50 one at a time through the space whereby to permit discharge of the pills one at a time through the opening in the wall.
